UNITED STATES PATENT OFFICE.

LYSLE L. HAZEN, OF JOPLIN, MISSOURI.

PUMP HEAD.

Application filed April 28, 1925. Serial No. 26,436.

This invention relates to an improved pump head, which is especially adapted to be used in connection with deep well pumps, and in which reciprocatory motion is imparted to the sucker rods by means of a crank disk and pitmans as distinguished from the walking beam type.

The general object of the invention is to provide a pump head of the type stated, which is comparatively simple and inexpensive in its construction and light in weight, which operates noiselessly and with the greatest possible efficiency, this being secured by a light running mechanism without shocks, and with perfectly balanced loads.

The detailed construction of the invention and its advantages will be more fully explained in connection with the accompanying drawings, which illustrate one embodiment thereof.

In the drawings:

Figure 1 is a side elevation of the invention.

Figure 2 is a front elevation thereof.

Figure 3 is a longitudinal sectional view.

Figure 4 is a transverse sectional view.

Figure 5 is a detail sectional view taken on the line 5—5 of Figure 3.

Figure 6 is a horizontal section taken on the line 6—6 of Figure 1.

The device is mounted on an upright frame 10, which is secured to a suitable base 11 above the mouth of the well in which the sucker rods 12 and 13 are adapted to reciprocate, the rod 12 reciprocating inside of the rod 13, which is hollow. Cross heads 14 and 15 are secured to the upper ends of the sucker rods 12 and 13, and are formed with channels which are guided for reciprocation on vertical guide bars 16 and 17 formed on opposite sides of the frame 10. As shown in Figure 6, each of these guide bars is rabbed to receive cleats 18, which are secured to the respective cross heads, so that the latter are limited to a vertical reciprocatory motion. The cross heads 14 and 15 are connected to pitmans 19 and 20 by means of which they are reciprocated.

A semi-circular trough 21 is secured to the upper end of the frame 10, and a complementary semi-circular cap or housing 22 is secured to the trough, and in connection therewith encloses the peripheral portion of a crank disk 23. The disk 23 is adapted to be supported by a series of rollers 24, which

are secured to spindles 25 within the trough 21, the spindles being supported by ball bearings 26 mounted within the sides of the trough. The crank disk 23 is formed with a circumferential groove 27, which is engaged by the edges of the rollers 24 on which the disk is supported. Oppositely disposed wrist pins 28 are mounted in the disk 23, and are connected with the upper ends of the respective pitmans 19 and 20. The disk 23 is provided with series of holes 29 arranged on opposite sides of its center, whereby the pitmans may be adjusted to vary their throw, and consequently the length of the stroke of the sucker rods.

The disk 23 is provided with gear teeth 30 on each side of the groove 27, these teeth being engaged by the teeth of a pinion 31 secured to a shaft 32, which is rotatably mounted within a journal box 33 at the upper side of the housing or cap 22.

The shaft 32 may be driven by any suitable means, as, for example, by means of a pulley 34 secured to the shaft, and connected by a belt 35 to a drive pulley 36 secured to the shaft 37 of a motor 38 mounted on the base 11.

The crank disk 23, which carries the entire load, is entirely supported by the rollers 24, which are mounted directly over the well, so that the center of the crank disk is directly in line with the vertical center line of the well. This insures the carrying of the load directly over the center of the well, and avoids overhung loads, such as are objectionable in pumps of the walking beam type. The sucker rods and pitmans are always under tension, thus avoiding buckling strains which occur in the inverted type of pump head, and in all double acting pumps.

The load is perfectly balanced. The crank pins 28 are set directly opposite each other, that is, 180° apart. The perfectly balanced load on all reciprocating parts, including the long heavy sucker rods, avoids the objectionable variation of stresses inherent in all pumps having overlapping strokes. The smooth and balanced crank motion causes the travel of the heavy sucker rods to be reversed with the least possible shock, thereby avoiding the unbalanced and destructive motion inherent in all double stroke pumps in which the strokes overlap.

The disk 23 and the rollers 24 run in a bath of oil which is contained in the trough 21, and this light running mechanism with

perfectly balanced loads and the absence of shocks results in the highest possible efficiency. By the construction, as shown and described, the utmost rigidity and perfect permanent alinement of the working parts are assured.

The wearing parts are of simple and inexpensive construction and easily replaced when worn. The simplicity of the construction 10 permits ready access to any part of the mechanism, and permits it to be readily disassembled when it is necessary to remove the pump from the well, or to dismantle it for any other reason.

15 While I have shown and described the detailed construction of the invention in what is at present regarded as the preferred embodiment thereof, it is apparent that various modifications may be made in the form and 20 relation of the various elements thereof without any material departure from the salient features of the invention. It is my purpose, therefore, to include all such modifications within the scope of the appended 25 claims.

What is claimed is:

1. In a pump head, the combination of a 30 crank disk disposed in a vertical plane, a semi-circular trough adapted to contain oil, a series of rollers mounted in said trough on which the crank disk is supported, a semi-circular cap secured to the trough and forming therewith a circular housing enclosing the peripheral portion of said crank disk, and means for rotating said crank disk.

2. In a pump head, the combination of a 40 crank disk disposed in a vertical plane and having a circumferential groove with gear teeth on either side thereof, a semi-circular trough adapted to contain oil, a series of rollers mounted in said trough and engaging in said groove to support the crank disk, a semi-circular cap secured to the trough and forming therewith a circular housing enclosing the peripheral portion of the crank disk, and a driving pinion mounted in the upper part of said cap and engaging the gear teeth on the crank disk.

3. In a pump head, the combination of a 50 crank disk disposed in a vertical plane, a housing enclosing the peripheral portion of the disk leaving the remainder of the disk exposed, said disk having a circumferential groove with gear teeth on each side thereof within the housing, spaced rollers mounted in the lower portion of the housing and engaging said groove to support the disk, and a drive pinion engaging the teeth on the upper portion of the disk and serving to hold 60 the disk on said rollers.

4. In combination, a crank disk, a housing 70 enclosing the peripheral portion of the disk leaving the remainder of the disk exposed, said disk having a circumferential groove with gear teeth on each side thereof

within the housing, and spaced rotatable elements mounted within the housing about the periphery of the disk and engageable therewith to center said disk within the housing, one of said elements having gear teeth engaging the teeth of the disk, and another of said elements having a smooth periphery engaging the groove.

5. In combination, a crank disk, a housing 75 enclosing the peripheral portion of the disk leaving the remainder of the disk exposed, said disk having a circumferential groove with gear teeth on each side thereof within the housing, rollers engaging the groove, a pinion engaging said teeth, said rollers and pinion being arranged in opposed relation within the housing so as to retain the disk between them, and a wrist pin secured to the exposed portion of the disk.

6. In a pump head, the combination of a 85 pump head disposed in a vertical plane, an arcuate trough adapted to contain oil, a plurality of spindles rotatably mounted in the sides of the trough and traversing the same, rollers secured on the respective spindles and engaging in said groove to support the crank disk, an arcuate cap complementary to the trough and secured thereto to form therewith a circular housing enclosing the peripheral portion of said crank 95 disk, and means for rotating said disk.

7. In a pump head, the combination of a 100 crank disk disposed in a vertical plane and having a circumferential groove with gear teeth on either side thereof, an arcuate trough adapted to contain oil, spindles rotatably mounted in the sides of the trough and traversing the same, rollers secured on the respective spindles and engaging in said groove to support the crank disk, an arcuate 105 cap complementary to the trough and forming therewith a circular housing enclosing the peripheral portion of said crank disk, and a driving pinion mounted in the upper part of said cap and engaging the gear teeth 110 on the crank disk.

8. A pump head comprising, in combination, two pitmans for reciprocating the sucker rods of the pump; a crank disk with which the two pitmans are connected; a 115 power driven shaft operatively connected with the crank disk for rotating the same and operating the sucker rods; and mechanical connections between the two pitmans and the crank disk, so constructed and arranged that the pitmans are connected to the crank disk at diametrically opposite points and at equal distances from the axis of rotation of the crank disk, and adjustment of the throw of both pitmans is permitted 120 without varying the equal spacing of both connections from said axis.

9. A pump head comprising, in combination, a pair of pitmans connected with the sucker rods of the pump; a crank disk with 130

which the two pitmans are connected at diametrically opposite points; a power driven shaft; a pinion on said shaft; said crank disk having peripheral gear teeth with 5 which the pinion meshes, thereby to drive the crank disk and reciprocate the sucker rods; a lubricant trough surrounding the lower portion of the crank disk, whose gear teeth thus pass through a lubricant bath; 10 a series of rollers within the trough supported on axes which are transverse of the trough and parallel to the axis of rotation of the crank disk; the crank disk being supported wholly by the rollers with which it 15 has peripheral contact; the rollers fitting into a groove provided on the periphery of the crank disk, so that any movement of the crank disk parallel to its axis of rotation is prevented; and means closing the trough and 20 guarding the remainder of the crank disk, while permitting free movement of the pitmans.

10. A pump head comprising, in combination, a pair of pitmans connected with the 25 sucker rods of the pump; a crank disk with

which the two pitmans are connected at diametrically opposite points; a power driven shaft; a pinion on said shaft; said crank disk having peripheral gear teeth with which the pinion meshes, thereby to drive the crank 30 disk and reciprocate the sucker rods; a lubricant trough surrounding the lower portion of the crank disk, whose gear teeth thus pass through a lubricant bath; a series of rollers within the trough supported on axes which 35 are transverse of the trough and parallel to the axis of rotation of the crank disk; the crank disk being supported wholly by the rollers with which it has peripheral contact; the rollers fitting into a groove provided on 40 the periphery of the crank disk, so that any movement of the crank disk parallel to its axis of rotation is prevented; the rollers having flat sides and V-shaped peripheries 45 and fitting into grooves which are shaped complementarily.

In testimony, that I claim the foregoing as my own, I have hereto affixed my signature.

LYSLE L. HAZEN.
